DESIGN FOR A CONTAINER CAP

Stanley Sapery, New York, N. Y., assignor to
Victor Metal Products Corporation, Brooklyn,
N. Y., a corporation of New York

Application January 25, 1943, Serial No. 109,345

Term of patent 14 years

(Cl. D58—26)

To all whom it may concern:

Be it known that I, Stanley Sapery, a citizen of the United States and resident of the Borough of Manhattan, city, county, and State of New York, have invented a new, original, and ornamental Design for a Container Cap, of which the following is a specification, reference being had to the accompanying drawing, forming part thereof.

Fig. 1 is a top plan view of a container cap showing my new design.

Fig. 2 is a front view of the same.

Fig. 3 is a bottom plan view of the same.

Fig. 4 is a fragmentary side elevational view

of the cap on an enlarged scale illustrating the details of one of the ribs.

Fig. 5 is a fragmentary enlarged plan view thereof.

The characterizing features of my design for the container cap shown reside in the fine serrations throughout the entire surfaces of the outstanding projections on the cap skirt as illustrated.

I claim:

The ornamental design for a container cap, substantially as shown and described.

STANLEY SAPERY.
